UNITED STATES PATENT OFFICE.

CECIL WATSON, OF LONDON, ENGLAND.

BUFFING AND DRAFT GEAR FOR RAILWAY AND OTHER ROLLING-STOCK.

1,062,312.

Specification of Letters Patent.

Patented May 20, 1913.

Application filed October 23, 1911. Serial No. 656,162.

To all whom it may concern:

Be it known that I, CECIL WATSON, a subject of His Majesty the King of Great Britain, and a resident of London, England, have invented a certain new and useful Improvement in Buffing and Draft Gear for Railway and other Rolling-Stock, of which the following is a specification.

This invention relates to improvements in buffing gear and more particularly to combined buffing and draft gear and has for its object to provide an improved arrangement giving an increased range combined with a graduation of the resistance to both compression and tension.

According to the invention the improved arrangement consists essentially of two springs placed in tandem around a single shaft or drawbar separated by a pair of preferably similar flanged ferrules, the sleeve portions of which are slotted so that one sleeve can slide through the other. These slotted ferrules are engaged with one another with the inner faces of their flanges in juxtaposition so that the slotted sleeve portion of each ferrule protrudes beyond the flange of the opposite ferrule. These ferrules being similar are interchangeable. The outer ends of the two springs also engage with ferrules, preferably unslotted, the sleeve portion of which projects inside the spring and is made of such a length as to come in contact with the end of the opposing slotted sleeve portion of the ferrules respectively separating the two springs so soon as either spring has been compressed to the required amount. The outer ferrules abut against fixed stops at either end of the arrangement.

To enable the invention to be fully understood it will now be described by reference to the accompanying drawings which illustrate by way of example several embodiments of the invention.

In the drawings:—Figure 1 is a sectional view showing the slotted ferrules carried by a fixed central bracket. Fig. 2 is a similar view but with the central bracket having a limited amount of play. Fig. 3 shows a face, sectional and a view in elevation of one of the slotted ferrules employed, the sleeve portion thereof being adapted to allow a second similar ferrule to slide therethrough. Fig. 3^a shows views similar to Fig. 8 of a second ferrule the sleeve portion of which is adapted to slide through the

sleeve portion of the ferrule shown in Fig. 3. Fig. 4 shows a modified arrangement in which the fixed or movable central bracket is omitted. Fig. 5 shows a modified arrangement of three springs. Fig. 6 an arrangement of four springs and Fig. 7 a modified arrangement of three springs.

In the simplest case as shown in Fig. 1, the arrangement consists of two springs A and B placed in tandem around a shaft or drawbar C and separated by a pair of preferably similar flanged ferrules D and E the sleeve portions of which are slotted so that they can be interchanged and one sleeve can slide through the other. The preferred construction of these ferrules is shown in Figs. 3 and 3^a. These slotted ferrules are engaged with one another with the inner faces of their flanges in juxtaposition so that the slotted sleeve portions of each ferrule protrude beyond the flange of the opposite ferrule. The outer ends of the two springs A and B also engage with preferably unslotted flanged ferrules F and G, the sleeve portion of which projects inside the spring and is made of such length as to come in contact with the end of the opposing slotted sleeve portion of the ferrules D and E respectively so soon as either spring has been compressed to the required amount. The outer ferrules F, G, abut against fixed stops 1, 1, 2, 2, respectively. The action of the arrangement when subjected to compressional or tensional strain is as follows:—The first effect is to compress one spring A against the ferrule flange D resting against the central stop bracket H until the ferrule F within that spring comes in contact with the sleeve portion of E. The second effect is that further pressure is transmitted through the slotted sleeve of E and its flange to the spring B on the opposite side of the central bracket which is then compressed. It follows from this arrangement that during the first portion of the stroke the resistance is equal to that of one spring A and that during the second portion the resistance is equal to that of the two springs A and B in parallel. It further follows that the sequence of operations is the same in either direction, so that it is equally applicable for buffing or draft gear. A further graduation of the resistance of the arrangement can be obtained by substituting for the fixed central stop bracket H a system of selective stops which permit a limited travel to either of the

inner flanged ferrules in the direction of the pressure while allowing free travel in the opposite direction. As shown in Fig. 2 this stopping action may be secured by a loose bracket or plate I between the flanges of the central ferrules D', E', the travel of which is limited in either direction by means of suitable stops K and L, the end ferrules in this arrangement being denoted by F' and G' respectively. With this arrangement on movement of the drawbar C in either direction both springs are first slightly compressed until the bracket I meets one or other of the stops K, L, when a single spring only is compressed. Further movement of the drawbar then causes both springs to be compressed again.

In the modification shown in Fig. 4 the fixed or movable bracket is omitted and one of the end ferrules F² or G is made shorter than the other. As shown ferrule F² is the shorter and as the system is compressed the first action will be to compress both springs A and B until ferrule D comes into contact with ferrule G² after which spring A only is further compressed until the ferrule E comes into contact with ferrule F² when both springs again take the pressure. The above arrangements therefore allow of a graduation of the resistance of the springs to both compression and tension. The graduations can be adjusted by varying the initial space between the ferrules and the position of the stops.

It will be evident that many arrangements of gear constructed according to this invention are possible for example:—In Fig. 5 an arrangement is shown in which three springs 20, 21, 22 are separated by two sets of oppositely arranged split ferrules 23, 24, and 25, 26. Ferrules 27, 28 are inserted in the ends of springs 20, 22, and secured to the draw bar 29. With this arrangement the action under compression is as follows:—

(1) The springs 20, 21, 22 are compressed in series. (2) Ferrule 24, meets the ferrule 25, causing springs 20, 22 to be compressed in series. (3) The ferrule 26 meets the ferrule 28, and spring 20 only is compressed. (4) Finally the ferrule 23 meets the ferrule 27 and the springs 20, 22 are compressed in series, in parallel with the spring 21.

Fig. 6 shows an arrangement of four springs 30, 31, 32, 33. A pair of oppositely arranged split ferrules 34, 35 are placed between the springs 30, 31, and another pair 36, 37 between the springs 32, 33. The springs 31, 32 are separated by means of a pair of oppositely arranged split ferrules 38, 39, which pass outside the springs and are adapted to make contact with the ferrules 40, 41 respectively. Further, ferrules

43, 44 are provided as shown. With this arrangement graduations of compression can be obtained as follows:—1. Four springs in series. 2. Three springs in series. 3. Two springs in series. 4. One spring in series. 5. Two springs in parallel. 6. Four springs in parallel.

Fig. 7 shows three springs 50, 51, 52, arranged on a draw bar 53, the latter being mounted in the link 54. One pair of oppositely arranged split ferrules 55, 56 are provided said ferrules being separated by the spring 51. Two ferrules 57, 58 are provided which coöperate with the other ferrules to produce the required sequence of action of the springs. With this arrangement graduation of compression can be obtained as follows:—1. Three springs in series. 2. One spring in series. 3. The equivalent of three springs in parallel.

I am aware that in buffing gear it has been proposed to use two springs first one singly and then both in parallel, and also in combined buffing and draw gear it has been proposed to use two or more springs working first singly and then in parallel, and I make no broad claim to such constructions.

What I claim is—

1. For a combined buffing and draw gear and similar purposes, a drawbar, springs in tandem on said drawbar, flanged ferrules sliding one within the other separating said springs, said ferrules being oppositely arranged, slotted sleeves on said ferrules projecting within the springs and ferrules having sleeve portions projecting inside the outer ends of the springs, the sleeves of the various ferrules coöperating on contact one with the other to regulate the sequence of the action of the springs substantially as described.

2. For a combined buffing and draw gear and similar purposes, a drawbar, springs in tandem on said drawbar, a stop bracket separating said springs, a flanged slotted ferrule passing through said bracket and adapted to compress one spring, a second flanged slotted ferrule passing through the first ferrule and adapted to compress the other spring, and ferrules having sleeve portions projecting inside the outer ends of the springs, the sleeves of the various ferrules coöperating on contact one with the other to regulate the sequence of the action of the springs substantially as described.

In testimony whereof I have hereunto set my hand in the presence of two subscribing witnesses.

CECIL WATSON.
